RAYMOND R. SMITH, OF CLEVELAND, OHIO, ASSIGNOR TO 3-0-3 CHEMICAL COMPANY, OF TOLEDO, OHIO, A PARTNERSHIP COMPRISING H. BRUCE STONE AND RAYMOND R. SMITH.

DESIGN FOR A DISPENSING-RECEPTACLE.

54,871.

Specification for Design.

Patented Apr. 13, 1920.

Application filed February 2, 1917. Serial No. 146,295. Term of patent 3½ years.

To all whom it may concern:

Be it known that I, RAYMOND R. SMITH, a citizen of the United States, residing in Cleveland, Cuyahoga county, State of Ohio, have invented a new, original, and ornamental Design for a Dispensing-Receptacle, of which the following is a specification, reference being had to the accompanying drawing, forming a part thereof.

The single figure in the drawing is a side view of the receptacle illustrating my new design.

I claim:

The ornamental design for a dispensing receptacle, substantially as shown.

RAYMOND R. SMITH.
